UNITED STATES PATENT OFFICE.

WILLIAM PRINCE-SMITH AND DAVID WATERHOUSE, OF KEIGHLEY, ENGLAND.

THREAD GUIDE FOR SPINNING, TWISTING, AND OTHER ANALOGOUS TEXTILE MACHINERY.

Application filed January 29, 1926, Serial No. 84,664, and in Great Britain July 16, 1925.

This invention relates to thread-guides for spinning, twisting and other analogous textile machinery, and the invention has for its object to improve the attachment of these guides and to facilitate the renewal of guides when necessary.

It is usual to employ guides composed of some suitable hard and durable material such as porcelain or hardened steel, and these by reason of their composition are manufactured as separate units and afterwards attached in a variety of different ways to the spinning or analogous machine of which they form part. For example these porcelain or steel thread-guides have been secured in place on the machine by means of one or more springs clamping the guide to its bracket, the guide sometimes being notched or recessed peripherally to receive a part to prevent rotation of the guide.

According to the present invention a thread-guide for a spinning, twisting or analogous textile machine is retained in place by means of an external spring anchored at one end to and embracing the part holding said guide and being so formed as to project through a slot in said part in order to engage a notch on the periphery of the guide, whereby rotary and vertical movement of the guide are prevented.

One constructional form of the invention is illustrated in the accompanying drawings, in which Figure 1 is a side elevation of a part of a textile machine into which a thread guide is fitted, Figure 2 is a plan view, and Figure 3 is a sectional plan view on line 2—2 of Figure 1.

1 represents a metal bracket, or other part of a spinning or like machine, which is apertured to receive a thread-guide or "pot-eye" 2.

This "pot-eye" 2 is slotted radially at 2^a in order to permit the yarn or thread to have access to its central bore, and externally said "pot-eye" 2 is formed with a notch 3 or other equivalent means of securing interlocking engagement with a "knee" 4 or its equivalent formed in a steel spring 5 adapted to encircle a portion of said bracket 1 (which is slotted at 1^a for admittance of said "knee" 4) to which bracket one end of said spring 5 is anchored by being turned in radially and inserted in an aperture 5^a formed for its reception in the side of the bracket 1. The position of this aperture 5^a relatively to the

"knee" 4 in the spring 5 is such that engagement of the "knee" 4 with the notch 3 positions the radial slot 2^a correctly in relation to the mouth of the apertured bracket 1 where-through the yarn or thread is passed into the "pot-eye".

It will be seen that the above described arrangement constitutes a very simple means of retaining "pot-eyes" or thread-guides in place and enables any one to be removed and renewed with the greatest facility merely by exerting pressure to spread the retaining ring sufficiently to release it from engagement with the "pot-eye" or guide.

What we claim is:

1. In spinning, twisting and other analogous textile machines, an apertured part to receive a thread guide, a radial slot serving as a thread passage into said apertured part, a thread guide fitting in said apertured part, 70 said thread guide having a central bore and a radial slot leading thereto and said radial slot being adapted to register with said thread passage in said apertured part, a peripheral slot in said apertured part, a radial aperture in said apertured part, a spring having one end anchored in said radial aperture, said spring encircling a portion of said apertured part, and means to cause said spring to engage and hold said 75 thread guide in said apertured part.

2. In spinning, twisting and other analogous textile machines, an apertured bracket to receive a thread guide, a radial thread passage in said bracket, a thread guide fitting into said bracket, said thread guide having a central bore and a radial thread passage therefrom adapted to register with said thread passage in said bracket, a peripheral slot in said bracket, a radial aperture in said bracket, and a spring encircling part of said bracket and having one end anchored in said radial aperture, said spring engaging and holding said thread guide in said bracket.

3. In spinning, twisting and other analogous textile machines, an apertured bracket to receive a thread guide, a radial thread passage in said bracket, a thread guide fitting into said bracket, said thread guide having a central bore and a radial thread passage therefrom adapted to register with said thread passage in said bracket, a peripheral slot in said bracket, a radial aperture in said bracket, and a spring encircling part of said bracket, one end of said spring being bent 100 105 110

into said radial aperture in said bracket, and part of said spring extending through said peripheral slot to engage and hold said thread guide in said bracket.

5. 4. In spinning, twisting and other analogous textile machines, an apertured bracket to receive a thread guide, a radial thread passage in said bracket, a thread guide fitting into said bracket, said thread guide having a central bore and a radial thread passage therefrom adapted to register with said thread passage in said bracket, a peripheral notch on said thread guide, a peripheral slot in said bracket, said peripheral notch and said peripheral slot being adapted to register, a radial aperture in said bracket, and spring encircling part of said bracket, one end of said spring being bent into said radial aperture in said bracket, said spring being formed to project through said peripheral slot to engage said notch on the periphery of said thread guide and to hold said guide in said bracket.

10. 5. In spinning, twisting and other analogous textile machines, an apertured bracket to receive a thread guide, a radial thread passage in said bracket, a thread guide fitting into said bracket, said thread guide having a central bore and a radial thread passage therefrom adapted to register with said thread passage in said bracket, a peripheral notch on said thread guide, a peripheral slot in said bracket, said peripheral notch and said peripheral slot being adapted to register, a radial aperture in said bracket, and spring encircling part of said bracket, one end of said spring being bent into said radial aperture in said bracket, and a knee formed on said spring, said knee projecting through said peripheral slot to engage said notch on the periphery of said thread guide to hold said guide in said bracket.

15. notch and said peripheral slot being adapted to register, a radial aperture in said bracket, and spring encircling part of said bracket, one end of said spring being bent into said radial aperture in said bracket, said spring being formed to project through said peripheral slot to engage said notch on the periphery of said thread guide and to hold said guide in said bracket.

20. 6. In spinning, twisting and other analogous textile machines, an apertured bracket to receive a thread guide, a radial thread passage in said bracket, a thread guide fitting into said bracket, said thread guide having a central bore and a radial thread passage therefrom adapted to register with said thread passage in said bracket, a peripheral notch on said thread guide, a peripheral slot in said bracket, said peripheral notch and said peripheral slot being adapted to register, a radial aperture in said bracket, and spring encircling part of said bracket, one end of said spring being bent into said radial aperture in said bracket, and a knee formed on said spring, said knee projecting through said peripheral slot to engage said notch on the periphery of said thread guide to hold said guide in said bracket.

25. In testimony whereof we affix our signatures.

WILLIAM PRINCE-SMITH.
DAVID WATERHOUSE.
